UNITED STATES PATENT OFFICE.

JOHN THOMSON, OF NEW YORK, N. Y., ASSIGNOR TO JOHN THOMSON PRESS COMPANY,
OF JERSEY CITY, NEW JERSEY, A CORPORATION OF NEW JERSEY.

ELECTRIC FURNACE FOR FUSING METALS.

1,214,841.

Specification of Letters Patent. Patented Feb. 6, 1917.

Application filed January 28, 1916. Serial No. 74,827.

To all whom it may concern:

Be it known that I, JOHN THOMSON, a citizen of the United States, and a resident of Manhattan, in the city, county, and State 5 of New York, have invented new and useful Improvements in Electric Furnaces for Fusing Metals, of which the following is a specification, reference being made to the accompanying drawings, forming a part hereof.

10 These improvements particularly pertain to furnaces adapted for fusing such metals as copper, zinc, lead, etc., and the objects hereof are to effect the named results with high thermal economy, rapidity, convenience and metallurgical efficiency.

In the drawings, which denote a preferred embodiment of the invention,

Figure 1 is a longitudinal center section taken as on the plane indicated by line A in 20 Fig. 2, except that the right hand lower portion thereof is taken as along the line A¹ of said Fig. 2.

Fig. 2 is a transverse center section taken as on the plane indicated by line B in Fig. 25 1; and

Fig. 3 is a plan view, the cover of the furnace being removed. Fig. 3 is a view taken as on the plane indicated by line C.

The furnace D is mounted upon a rocker, 30 4, whereby the structure is capable of being rocked, as denoted by arrows d, e. The center of the rocker-arc should preferably be located somewhat above the top of the furnace to insure, normally, stable equilibrium.

35 The single rectangular chamber E contains all of the furnace elements which are inclosed by a conveniently removable cover or roof, which may be formed of free slabs, 5, possessed of good resistance to heat conduction.

40 The heating element is a suspended radiating resistor comprised in a pair of carbon plates, 6, 7, having staggered slots, as 8, forming a zig-zag electric circuit. The 45 plates are attached to terminals, 9, 10, passing out through a wall of the furnace, but their inner ends are joined, whereby to be electrified in series, by a carbon connector, 12, resting upon refractory blocks, 13, 14.

50 Immediately above the resistor is a shallow tank, 15, in which the material to be fused is placed. This tank is provided with a flange, 16, which rests upon an inner course of the brick-work, as 17. This flange per-

forms the functions of sustaining the tank 55 and also in coöperation with the tank itself of completely inclosing the resistor. If the tank is formed of fragile material, or if the imposed load is excessively heavy, one or more supporting pillars, as 18, may be applied. A free space is provided around the outer edge of the flange which is packed with cement, as 19; the object thereof being to seal the resistor-chamber against the entrance of air.

60 One end of the tank is provided with a shallow spout, as 20, extending to the exterior of the brick-work, and beneath it is a recess, 21, having at its inner end, and contiguous to its lower surface 22, on a line 70 with the bottom, 23, of the tank, a tap-hole 24 which is normally closed with removable granular material, as 25.

When the tank is in a horizontal position, the bath of melted metal will be as denoted 75 by the broken lines 26.

In any convenient portion of the furnace, or as shown in Figs. 2 and 3, a block 27, is set having an axial or sloped bore, 28.

80 The foregoing briefly, but it is believed adequately, describes the several elements of the furnace, whose operation will now be related.

The tank is susceptible of being very quickly and easily charged with any form of 85 material, such as metal in pigs, slabs, or bulky scrap, by simply removing one or more of the cover-tiles.

As the inner surfaces of the sides of the tank are not in contact with the chamber-walls, the heat from the resistor is free to act upon practically its entire surface, and by the liberal use of heat-insulating bricks formed of the most effective material fully 90 85% to 90% of the thermal energy must 95 necessarily flow to the relatively large and cooler surface of the tank, and thence through its walls to the contained charge. The thermal efficiency is all the more pronounced because of the fact that the resistor-100 plates may be set, as shown, quite closely to the bottom of the tank.

105 By introducing, through the bored block, oil or zinc, as 29, inert gas or fume is produced within the resistor-chamber, consuming or displacing the air therein, hence no burning of the carbon can take place. Any hydrous vapors, or excess of gas or fume.

may be consumed at the outer end of the block, as 30.

When a bath of hot metal will have been produced, as 26, all that is necessary to effect its removal is to slightly rock the furnace and pour from the spout, 20. In practice, a swing of from 5° to 15° as in Fig. 1, is ample. But it is to be here particularly observed that the run-off will be from the upper portion of the bath; and also that, unless the furnace is swung to an excessive extent, a portion of the fused metal will be retained, or as indicated by the broken lines, 31. It is for the removal of this pocket of metal that the tap-hole, 24, is provided. The particular object of being able, if desired, to retain a residuum of a melt, or of a series of melts, or of a more or less continuously conducted melting operation, is to permit the precipitation, by difference of density, of a heavier metal out of a lighter; such, for example, as lead or iron out of zinc. Then, when a sufficient accumulation of the denser metal, or metals, has been accumulated—and in usual practice such would be much the lesser in quantity—the tap-hole is opened and it is separately evacuated. If the metal to be thus separated by density is of considerable relative volume, then a portion of the bottom of the tank may be depressed, to form a sump, or the same effect can be realized by keeping the furnace slightly tilted so that the denser metal will constantly flow toward the tap. If for any reason preferred the fused metal can be easily and quickly removed by means of ladles, that is, dipped out. So, too, the surface of the bath can be readily and effectively skimmed. When the metal to be fused is, say, zinc or lead, the tank may be formed of cast iron or steel, while in the instance of copper, or metals having a high melting point the usual graphite-clay mixtures used in the construction of crucibles are necessary. However, in view of the manner in which the tank is sustained, and its relative shallowness, the sectional stresses are quite nominal; whereby the thickness of wall need not be ex-

cessive and the obstruction to the transfer of heat is minimized.

The furnace as herein described is exceedingly compact; is inexpensive to construct; the cost of maintenance is practically a negligible factor and a bath of hot metal may be maintained within a few degrees of variability by a merely nominal input of current.

Various details may be modified without evasion of the essence of the invention; as, for example, the furnace may be tilted or swung from axial bearings instead of being rolled on a segmental arc, and the cover may be made as a monolith to be slid off or tilted.

What I claim is:

1. An electric metals fusing furnace provided with a chamber whose bottom, sides and ends are lined with refractory material; a radiating carbon resistor suspended in said chamber and an outer-lying inclosing melting tank whose rim is in contact with the upper edges of the chamber-walls but having a free space around its sides and between its bottom and the resistor.

2. An electric metals fusing furnace having a carbon resistor suspended within an open topped refractory chamber, an open topped melting tank completely inclosing the said chamber, the bottom and sides of which tank are in free space to be acted upon by directly radiated and reflected heat emitted by said resistor and a removable cover above the tank.

3. An electric metals furnace having an open topped melting tank serving to inclose the top of a refractory chamber, a suspended carbon resistor beneath the tank and acting thereon by radiation, a pouring spout on or at one end of said tank and a rocker, upon which the furnace is mounted, the center of whose arc is located above the furnace.

This specification signed and witnessed this 26th day of January, A. D., 1916.

JOHN THOMSON
